Attorney, Agent, or Firm—Lerner, David, Littenberg, Krumholz & Mentlik

[57] CLAIM

The ornamental design for a water bottle, as shown and described.

DESCRIPTION

FIG. 1 is a perspective view of the water bottle in accordance with my new design;

FIG. 2 is a top plan view thereof;

FIG. 3 is a right side elevational view thereof, the left side elevational view being a mirror image of the right side elevational view;

FIG. 4 is a rear elevational view thereof;

FIG. 5 is a front elevational view thereof; and,

FIG. 6 is a bottom plan view thereof.

The broken line showing of the cap is for illustrative purposes only and forms no part of the claimed design.
